T. W. Johnston,

Lifting Jack.

NO 99,090.

Patented Jan. 25, 1870.

Fig. 1.

United States Patent Office.

THOMAS W. JOHNSTON, OF RICHMOND, MAINE.

Letters Patent No. 99,090, dated January 25, 1870.

IMPROVEMENT IN CARRIAGE-JACKS.

The Schedule referred to in these Letters Patent and making part of the same.

Be it known that I, THOMAS W. JOHNSTON, of Richmond, in the county of Lincoln, and State of Maine, have made an invention of an original and useful Carriage-Jack; and do hereby declare that the following is a description thereof, taken in connection with the accompanying drawings, which form a part of this specification, in which—

Figure 1 is a perspective representation of my invention;

Figure 2 being a vertical and longitudinal section of the same.

The invention herein described is intended to secure, in a carriage-jack, practically, low cost, durability, and effectiveness, as well as great variation in range, the device also possessing the advantage of being susceptible of operation by one hand of the operator.

The invention consists in the adoption of an upright sliding bar, the perpendicularity of which is maintained by a tubular post, within which it slides and is supported, the front or working-face of such bar being formed with a range of shallow teeth, and with a series of notches or depressions, the former being taken into by a tripping-pawl or pallet pivoted to the upper part of the post before mentioned, and the latter by a horn projecting inwardly from a long handle or lever, suspended from the pivot of the pawl, and somewhat below it, the nature and arrangement of the said lever being such that it serves the three-fold purpose of a means of elevating the slide bar or riser, of releasing the grip of the pawl upon the same, and of a brake or drag, to prevent too sudden a descent of the said slide bar and its load, otherwise ensuing from the release of the pawl, the whole being as hereinafter explained.

In the drawings before alluded to as accompanying this specification, and which illustrate my invention—

A denotes an upright tubular post, the outer or front face of which is open for about one-half its length from the top, as shown at a, the lower part of this post terminating in a broad flat base, which serves as a steady means of support to the device.

Sliding freely within the bore of the post A, is seen a slide bar, b, this bar being of about equal length with the post, and being provided at top preferably with a shelf or pad, c, for supporting the axle of a wheeled vehicle or other object which is to be raised from off the surface of the earth or of a floor.

The front and general face of the bar b is serrated, or formed with a range of saw-teeth, d, d, &c., and also with a series of notches or cavities, e e, &c., the former greatly outnumbering the latter.

To the upper part of the post A, and so disposed as to play within its orifice a, is situated a swinging or pendulous tripper or pawl, f, this pawl being suspended between and pivoted to ears g g, formed upon

the post and at opposite sides of its orifice a, as seen at a'.

The upper and rear part of the pawl f, or that part which is disposed above its point of support, is provided with an integral eccentric or cam, h, the periphery of which is abraded or serrated, in order to take a firm hold of the bar b, and prevent its clandestine descent.

B, in the accompanying drawings, represents a long lever, which is fulcrumed, near one end, to short links or bars i i, depending from the pivot a', and upon opposite sides thereof, the fulcrum of this lever being shown at j.

The shorter and inner arm or horn of the lever B is capable of either entering one of the notches of the bar b, or of abutting against the lower end of the pawl f, as the case may be, the mode of suspending it permitting this to be done.

In operating with the implement or jack made as above described, it is to be placed below the axle of the carriage, and near its wheel.

By imparting tilting motions to the lever B, in manner as will be apparent to any intelligent person, the bar or riser b and its load may be elevated without action on the part of the pawl, and the wheel removed from contact with the earth or floor, the pawl f serving, by means of its eccentric, as a hold-fast, to prevent descent of the bar b, upon releasing the pressure upon the lever.

When the carriage-axle and wheel are to be lowered, the horn of the lever B is to be withdrawn from the notch of the bar which it may at the time be in, and forced against the lower end or tail of the pawl f. This action of the lever removes the hold of the pawl upon the bar, and permits it and its load to fall. Should this descent of the bar and its load be too sudden and rapid, the pressure of the lever upon the pawl should be maintained, thus compelling the latter to serve as a brake to retard the speed of such parts.

Owing to the length of the bar b, a great range is imparted to the movements of the same.

The device, when constructed of cast-iron, as may be done, if desirable, is very strong and durable, and may be produced at comparatively low cost, while, as before observed, all its motions may be guided by one hand of the operator.

Claims.

I claim—

1. A "carriage-jack," so called, consisting of a tubular post or its equivalent, carrying an upright toothed or notched bar, having two series of teeth or notches, as described, and provided with the pawl f and lever B, organized and operating as explained.

2. The combination of the bar b, pawl f, and lever

B, under such an arrangement that the latter serves the threefold purpose of elevating such bar, of releasing the hold of the pawl upon it, and of serving, in connection with such pawl, as a drag or brake upon the bar, for the purpose, essentially, as before described.

3. The construction of the bar or riser *b*, as containing two series of teeth or notches, one being for

action with the pawl *f*, to prevent descent of such bar, and the other being the agency whereby the intermittent elevations of the bar are effected, in manner and to produce results before explained.

THOMAS W. JOHNSTON.
